United States Patent Office

Des. 194,974
Patented Apr. 9, 1963

194,974

MULTIPLE SEATING UNIT

George Kasparian, 9562 La Tijera Blvd.,
Los Angeles, Calif.

Filed Oct. 4, 1961, Ser. No. 66,961

Term of patent 14 years

(Cl. D15—11)

Fig. 3

Fig. 4

FIGURE 1 is a perspective view of a multiple seating unit showing my new design;

FIGURE 2 is an end elevational view of the multiple seating unit shown in FIGURE 1;

FIGURE 3 is a front elevational view thereof; and

FIGURE 4 is a top plan view thereof.

I claim:

The ornamental design for a multiple seating unit, substantially as shown.
